UNITED STATES PATENT OFFICE.

HEINRICH TRAUT, OF MUNICH, GERMANY.

ELECTRIC ARC LAMP FOR PHOTOGRAPHING.

Application filed December 24, 1926, Serial No. 156,956, and in Germany December 28, 1925.

This invention relates to an electric arc lamp for photographing purposes which is arranged so that arc light can be used for photographing at any place where electric light contacts exist. Owing to its richness 5 in short-wave rays the arc lamp is superior for photographing purposes than incandescent lamps of high candle power. According to the invention the arc lamp is accommodated in a case which can be as easily 10 carried in the pocket as a cigar case and which is adapted to be connected with any wall socket so that the lamp can be carried on a handle and brought towards the object 15 to be photographed to light the same, the open cover of the case serving at the same time as reflector for the arc light.

An embodiment of the invention is shown in the accompanying drawing, by way of 20 example, in which

Fig. 1 shows the arc lamp in side elevation, the case being closed.

Fig. 2 is a top plan view of Fig. 1.

Fig. 3 shows in cross section on line 3—3 25 of Fig. 1 the case in open position.

The arc lamp is of the commonly used simple type without regulation and comprising parallel carbons which, after they have been connected to a source of current 30 with interposition of a corresponding resistance for reducing the existing voltage to about 40 volts by a simple contact with the carbon, are ignited by being touched with a carbon. The two carbons K, K' are arranged, according to the invention, in a carrier J, J'. Two covers H, H' are pivotally mounted on this carrier so that they form, together with the carrier, a closed case for the carbons after they have been 35 closed. The carrier consists of two side elements, J, J' of insulating material spaced by means of spacing blocks B, B'. These side elements are connected the one with the other by a plate C of refractory insulating material. In the gap between the two side 40 elements J, J' contact pieces D, D' comprising each a contact plug S, S' are inserted and rigidly connected to the side elements by means of screws. The two carbons K, K' 45 traverse each a bore of the plate C and project each through a bore E, E' respectively of the contact pieces D, D' respectively, in which they fit tightly so that they are securely held in said bores. These bores E, E'

extend through the contact pieces from one end to the other so that the carbons project into the gap between the side elements J, J' and can be pulled out according to requirement. Broken off pieces of the carbon or short remainders of carbon can be pushed 50 out through the bores. The current contact between the contact pieces D, D' and the carbons is ensured by the tight fitting of the carbons in the contact pieces. Onto the plug contacts S, S' a flat contact element F with 55 the cables is mounted, said contact element F fitting into the gap between the side elements of the carrier.

The two covers H, H', forming the case, are pivotally mounted in the top end and in 60 the lower end of the side elements J, J' by means of pivot pins G, G' and L, L'. The covers have inwardly curved edges which are of such width that, when the covers are closed, the front portion of the carrier and 65 the carbons are accommodated in the case. One of the covers has a spring hook M. Around the pivot pins G, G' and L, L' spiral springs N, N' are wound, which securely 70 hold the covers in the open position. The covers are mounted pivotally at the end sides by means of flaps of their bent flanges 75 so that, at a certain angular position of the two covers the one with regard to the other, the inner edge of each cover, which has no 80 flange, bears against one side wall of the carrier, the open position being thus limited. By means of grooves pressed into the inner surface of the covers, ribs O, O' are formed 85 near the inner edge of the covers, said ribs reinforcing the covers. The inner sides of each cover forms a reflecting surface so that 90 the covers serve as reflectors for the arc-light.

The portion of the carrier which is situated behind the open covers serves as handle 95 for holding the lamp when the same is in use. At one end of the carrier a plate P is fixed by means of screws on the two side elements of the carrier and into this plate 100 a handle Q is screwed which carries a carbon designed for igniting the lamp. This carbon projects into the gap between the side elements J, J' of the carrier so that it 105 is well protected against breaking.

Only one pair of carbons is shown on the drawing; there might, however, be provided two or more pairs of carbons. A cor-

responding number of contact pieces D, D' have to be provided in this case which are to be series-connected by means of the carbons.

I claim:—

5. 1. An electric arc lamp for photographing purposes, comprising in combination, a case consisting of two covers, the inner surfaces of which serve as reflectors, a carbon carrier composed of two elements of insulating material spaced the one from the other and on which said covers are pivotally mounted, carbons in said carrier, contacts for said carbons, and means for connecting said contacts with any existing light contact.
10. 2. An electric arc lamp for photographing purposes, comprising in combination, a case consisting of two covers the inner surfaces of which serve as reflectors, a carbon carrier forming a handle composed of two elements of insulating material spaced the one from the other and on which said covers are pivotally mounted, contact pieces tightly fitted in the gap between said two side elements of said carrier, carbons mounted in said contact pieces, and means for connecting said contacts with any existing light contact.
15. 3. An electric arc lamp for photographing purposes, comprising in combination, a case consisting of two covers the inner surfaces of which serve as reflectors, a carbon carrier forming a handle composed of two elements of insulating material spaced the one from the other and on which said covers are pivotally mounted, a plate connecting the lower ends of said side elements of said carrier and having two bores, contact pieces tightly fitted in the gap between said two side elements of said carrier and having each a continuous bore, carbons mounted in said bores of said contact pieces so that said carbons project into said gap in the carrier, and means for connecting said contacts with any existing light contact.

totally mounted, a plate connecting the lower ends of said side elements of said carrier and having two bores, contact pieces tightly fitted in the gap between said two side elements of said carrier and having each a continuous bore, carbons mounted in said bores of said contact pieces so that said carbons project into said gap in the carrier, and means for connecting said contacts with any existing light contact.

4. An electric arc lamp for photographing purposes, comprising in combination, a case consisting of two covers the inner surfaces of which serve as reflectors, a carbon carrier forming a handle composed of two elements of insulating material spaced the one from the other and on which said covers are pivotally mounted, a plate connecting the lower ends of said side elements of said carrier and having two bores, contact pieces tightly fitted in the gap between said two side elements of said carrier and having each a continuous bore, carbons mounted in said bores of said contact pieces so that said carbons project into said gap in the carrier, means for connecting said contacts with any existing light contact, a plate fixed on the top ends of said side elements of said carrier, a handle screwed into said plate, and a carbon for igniting the lamp carbons and fixed in the lower end of said handle so that it projects into said gap in the carrier.

In testimony whereof I affix my signature.
HEINRICH TRAUT.
